UNITED STATES PATENT OFFICE.

ALMERON MCKENNEY, OF MAUMEE CITY, OHIO.

IMPROVEMENT IN RAILWAY-RAIL JOINTS.

Specification forming part of Letters Patent No. 134,298, dated December 24, 1872.

To all whom it may concern:

Be it known that I, ALMERON MCKENNEY, of Maumee City, in the county of Lucas and in the State of Ohio, have invented certain new and useful Improvements in Railroad Splice; and do hereby declare that the following is a full, clear, and exact description thereof, reference being had to the accompanying drawing and to the letters of reference marked thereon making a part of this specification.

The object of my invention is to more perfectly support the joint between two adjoining railroad rails, by giving a direct vertical bearing on the supporting-plates instead of a lateral strain, as is the case where the said plates must rest upon slanting bearings under the head and on the foot of the rail. In the latter case, which is the usual plan heretofore employed, when the weight of the train comes upon the joint the effect is to produce a great strain upon the bolts by the wedging effect on the plates caused by the downward pressure of the slanting head of the rail. Besides the great weight of the passing train when there is a little depression at the joint, every passing wheel gives a heavy blow, as of several tons weight falling a short distance, and crowding the plates apart, destroying the threads of the screws or setting them out of their proper angles, so that the nuts become loosened and cannot again be made to remain tight when turned.

These difficulties are entirely obviated by my invention, which consists in providing the rails with an upper and lower groove, within which are fitted supporting-plates, which are held by clamp-bolts and locking-plates, as more fully hereinafter set forth.

In order to enable others skilled in the art to which my invention appertains to make and use the same, I will now proceed to describe its construction and operation, referring to the annexed drawing, in which—

Figure 1 is a perspective view, and Fig. 2 a cross-section, of my railroad splice.

A A represent the ends of two adjoining railroad rails. In the under side of the head of the rail is formed a longitudinal groove, a, and in the upper side of the foot of the rail is

formed another longitudinal groove, b. These grooves I have shown a trifle deeper on the inside next to the neck of the rail; but I do not desire to confine myself to any certain shape of said grooves, as any depression or cavity by which a projection is formed outside of the plates will answer the purposes to keep the plates from spreading outward. In the grooves a b is placed the supporting-plate B, which grooves secure an inward pressure instead of an outward strain of the plates, leaving but very little for the fastening-bolts to do. The edges of the plates B should be made to correspond with the shape of said grooves.

By using two of the clamp-bolts patented by me in 1871, and the locking-plate herein described, a cheap, substantial, and reliable support to the joint is formed, without the encumbrance of jam-nuts and nut-locks.

C C represent the said clamp-bolts, which are constructed with a round shank, e, having a semi-spherical head, d, on one end, and a flat semicircular head, f, on the other end. The head f is passed through mortises in the rail and plate, and then turned around, which fastens the plate sufficient for all purposes. The two bolts C C are then locked by means of a plate, D, resting upon the foot of the rail, and having notches in its upper edge to fit over the heads. This plate is held in place by a spike, h, which prevents it from slipping off, and the plate avoids the possibility of the clamp-bolts turning back and the joint becoming loosened.

Having thus fully described my invention, what I claim as new, and desire to secure by Letters Patent, is—

In combination with railroad rails having grooves or their equivalents formed in their heads and feet and supporting-plates placed in said grooves, the clamp-bolts C C and locking-plate D, substantially as and for the purposes herein set forth.

In testimony that I claim the foregoing I have hereunto set my hand this 22d day of June, 1872.

ALMERON MCKENNEY.
